UNITED STATES PATENT OFFICE.

LEON WYGODSKY, OF NEW YORK, N. Y., ASSIGNOR TO WYGODSKY ENGINE COMPANY,
OF NEW YORK, N. Y., A CORPORATION OF DELAWARE.

ENGINE.

1,114,217.

Specification of Letters Patent.

Patented Oct. 20, 1914.

Application filed December 26, 1913. Serial No. 302,893.

To all whom it may concern:

Be it known that I, LEON WYGODSKY, a subject of the Czar of Russia, and a resident of New York, in the county of New York

5 and State of New York, have invented certain new and useful Improvements in Engines, of which the following is a specification.

My invention relates to improvements in 10 engines, and particularly to improvements in engine beds or frames. The improved engine frame or bed herein illustrated and described is particularly intended for internal combustion engines, of the single- 15 acting type, but is likewise adapted for other types of engines, including air compressors, vacuum pumps, and water pumps.

My invention comprises a unitary bed structure comprising side members connected integrally at one end only and connected at the other end by means of adjustment rods whereby the said side members 20 may be sprung more or less to bring them into exact relative positions.

25 My invention further comprises a construction wherein the engine cylinder is formed integrally with the said side members, these side members being connected at one end through the cylinder and being connected at the other end by adjustment rods 30 as previously stated.

My invention further comprises an engine frame comprising a cast metal main frame member of U-form, and rolled, forged, or 35 pressed tension members, which tension members further serve as supports for a suitable traveling crane.

Other features of my invention will be pointed out hereafter.

40 The objects of my invention are to increase the strength and decrease the weight and cost of engine frames, particularly frames which are required to withstand excessive shocks; to reduce loss due to warped 45 castings, to provide an engine frame so constructed that, even though warped in the casting, it may be drawn into correct form, to provide an engine frame wherein tension stresses are taken by rolled, pressed, 50 or forged members, to provide in connection with the engine frame a convenient support for a suitable hoist, to provide improved means for the connection of valve gear parts to the frame, and generally to produce an

engine frame which, for its weight and size, 55 is stronger than any other frames heretofore used, is less expensive to cast and machine, and which is neat in appearance.

I will now proceed to describe my invention with reference to the accompanying 60 drawings, and will then point out the novel features in claims.

In the drawings: Figure 1 shows a side elevation of an engine frame embodying my invention; Fig. 2 an end view thereof, the 65 cylinder head being omitted as not being, in a strict sense, a part of the engine frame. Fig. 3 shows a front elevation of the engine frame. Fig. 4 shows a central longitudinal vertical section of the engine frame, and 70 Fig. 5 shows a top view of that frame. Fig. 6 shows a side elevation of the rear portion of the engine with cylinder head, valve gear bracket in place thereon, and Fig. 7 shows a top view of the same parts. Fig. 8 75 shows a side elevation of the front portion of the engine, and shows the hoist in place on the longitudinal tension members of the frame. Fig. 9 is a front elevation of the engine with the hoist in place thereon. Fig. 10 is a central longitudinal vertical section 80 of the front portion of the engine and of the hoist. Fig. 11 is a detail top view of the removable valve gear bracket.

The engine frame shown in the drawings 85 comprises a cast main frame member 1 having formed, as a part of it, the engine cylinder 2, said frame comprising also longitudinal tension rods 3 and transverse distance or adjustment rods 4 and 5. The member 1 is 90 of U-form comprising sides connected at the rear through the cylinder 2. The front portions of these sides are connected only through the distance rods 4 and 5. This frame 1 carries the bearings 6 for a suitable 95 crank shaft 7. The engine frame shown is for a horizontal engine, and is provided, at front and rear, with upwardly extending struts, 8, through suitable apertures in which the longitudinal tension rods 3 pass. These 100 tension rods 3 are provided with screw threaded nuts 9, 9, and 10, 10. The transverse tie bars 4 and 5, which also pass through suitable holes at the tops of the struts 8 and at the lower front portion of 105 the frame, are provided with similar screw nuts 11. In the case of engine frames which provide two bearings for a crank shaft, the

crank arms of such shaft rotating between the bearings, it is usually found practically impossible to produce castings for such frames which are true, or nearly so. Even though the pattern by which the mold for the frame was made be true (and these patterns usually warp) the casting itself is apt to warp during cooling. As a result, it is frequently found that a casting is too badly warped for use, and even when the casting is sufficiently true for use excessive machining is often required because of warping. Cast iron, the usual material of engine frames, though usually regarded as rigid, is not absolutely so, and is capable of slight flexure through members of considerable length. The sides of the cast member 1 of my engine frame being connected only in the rear, it is possible, by means of the distance rods 4 and 5, and the screw nuts 11 thereon, to draw said sides into correct relative relation, even though the casting be considerably warped.

It is well known that internal combustion engines subject their frames to excessive shock; and for this reason the frames of such engines, particularly of large internal combustion engines, are usually extremely massive in construction. It will be apparent that in an engine frame such as shown in the drawings, a large part of the stress due to the operation of the engine is taken by the members 3, which, because they are formed from rolled, forged or pressed steel bars, and are at a considerable distance from the center of effort, are well able to withstand great stresses. Because these members 3 of the frame take a large portion of the stress, the cast member 1 of the frame may be relatively light without sacrifice of strength.

The attachment of the valve gear parts to the engine bed or frame is often a matter of considerable difficulty, involving the machining of a number of surfaces. According to my invention, for this purpose I provide the engine bed 1, at its rear end, and to one side of the cylinder 2, with a rearwardly projecting boss 12, designed to be flush at its end with the end of the engine cylinder 2. In facing off this end of the engine bed, the end of the boss 12 is faced off at the same time that the end of the cylinder 2 is faced off, and with the same setting of the facing tool. It is then easy to secure to this boss a suitable bracket 13, (Figs. 6, 7 and 11), this bracket 13 providing bearings and supports for the cam shaft and various other parts of the valve gear. I also provide frame member 1 with other bosses 121 and 122, flush with the end of the cylinder 2, and which therefore are faced off at the same time that the engine cylinder 2 is faced off, and with the same setting of the facing tool. Boss 121 is for connection of an air duct, not shown, leading to the air admission valve of the cylinder head; air for the cylinder being drawn,

through a duct 123, from the interior of the frame, the frame serving as a muffler for the air intake. Boss 122 is provided for connection to the engine frame of a water pipe to supply cooling water to a jacket of the engine cylinder.

It is often necessary to remove the connecting rod, crank shaft, and piston of an engine such as shown in the drawings, and as these parts are exceedingly heavy, in engines of ordinary size, and as these parts are more or less inaccessible, the removal of these parts is often a very difficult task. I have found that the tension members 3 of my engine frame provide a particularly convenient support for a hoist to facilitate the removal of these heavy parts of the engine, and in Figs. 6, 7, 8 and 9 I have illustrated such a hoist 16, resting on these tension members 3; the said hoist comprising side members 17 connected by distance rods 18 and provided with saddles 19 adapted to rest upon the tension members 3 and to slide therealong, said tension members 3 constituting ways for the hoist. The hoist itself 90 may be of any suitable construction, and in the construction shown comprises a shaft 20 supported in bearings in the side members 17, and carrying a worm wheel 21 with which a worm 22 engages as shown. 95 The shaft 20 is also provided with suitable sprockets 23, over which suitable hoisting chains 24 may pass. I have shown in Fig. 10 one of these chains as provided with a suitable shackle 25 for convenient connection 100 to the arms of the crank shaft 7. It will be apparent that the hoist located as shown in Figs. 1 and 4, is very conveniently located for the lifting or lowering of the crank shaft. It will be apparent that this hoist, 105 when moved backward somewhat along the tension members 3, will be equally convenient for lifting the connecting rod or for lifting the piston as the latter is slid out of the engine cylinder; also for lifting off the 110 rear cylinder head 3; for which purpose the rods 3 extend somewhat to the rear of the rear struts 8, so that the hoist may be mounted on such rearward extensions.

The engine is provided with the usual 115 side shaft 26 driven from the crank shaft 7 by gears 27 and 28, and having near the front of the engine bed, a bearing 29, as is usual. At its rear said side shaft has bearings in the bracket 13, removably secured to 120 the boss 12, previously referred to. This bracket 13, besides having bearings for the shaft 26, has other bearings for various other portions of the valve gear. While I have illustrated a particular valve gear (described and illustrated more fully in my companion application docket No. 4210—) I do not deem it necessary to illustrate and describe this valve gear fully herein, as any suitable valve gear might be used so far as 125 130

the present invention is concerned. Since the main portions of the valve gear are carried by the removable bracket 13, and since the side shaft 26 may be made in two parts, 5 connected by coupling 30 (Fig. 6), or other equivalent construction permitting ready attachment or detachment of the valve gear cams carried by the bracket 13 from the front portion of that shaft 26, the valve gear 10 is very readily removed from the engine by the removal of the bracket 13, and is very readily assembled, and since this bracket 13 is secured to the engine frame, rather than to the cylinder head 31, the cylinder head 15 may be removed or renewed, when required, without dismounting the valve gear. In many of the present internal combustion engines, the valve gear is supported, in large part at least, by the cylinder head. The 20 cylinder head is the portion of the engine which is most apt to require removal from time to time and which not infrequently is injured to such an extent as to require renewal. When the valve gear is supported in 25 large part on the cylinder head, fitting a new head involves, not only the fitting of the head to the cylinder, but also the fitting of the valve gear to the cylinder head; and in many engines this is an exceedingly difficult and expensive operation. Since in my 30 engine the valve gear is supported by a bracket secured to the engine frame, instead of to the cylinder head, removal and replacement of the cylinder head is effected 35 without disturbing the valve gear. Moreover the fixing of the valve gear bracket to the bed makes possible the machining of the seat for that bracket on the bed, and makes possible precise location of the bracket, thus 40 permitting interchangeable manufacture of these parts; whereas when the valve gear bracket is carried by the cylinder head, the fitting of the valve gear must be done after the cylinder head is in place; and exact interchangeability is difficult to secure. 45

The engine cylinder, 2, in the particular construction shown in Fig. 4, is designed to receive a liner within which the piston of the engine will work, the space between the 50 cylinder and liner constituting the usual cylinder cooling jacket. As such liners are in common use in large engines I do not deem it necessary to illustrate the liner herein, or the particular means of connecting such liner to the engine cylinder.

What I claim is:

1. An engine frame of approximately U-form, the sides of the U integrally connected at the rear and provided with a distance 60 rod connecting them at the front.
2. A combined engine frame and engine cylinder of general U-form provided at its rear end with an engine cylinder constituting an integral portion of the frame, the 65 sides of the U being connected at the rear

through such engine cylinder and being provided with a distance rod connecting their front ends.

3. An engine frame comprising a frame member of general U-form, the sides of the U integrally connected at one end and being connected by a distance rod at the other end, said sides provided at front and rear with projecting struts, and tension members connecting said struts. 75

4. An engine frame of approximately U-form, the sides of the U integrally connected at one end, and a screw rod extending through apertures of the sides at the other end and provided with a nut whereby said 80 sides may be drawn into proper position.

5. An engine frame of approximately U-form, provided at one end with an engine cylinder constituting an integral portion of the frame, and a screw rod passing through 85 apertures in said sides near the other end of the frame and provided with a screw nut whereby said sides may be drawn into proper position.

6. An engine frame comprising a frame member of general U-form, the sides of the U being integrally connected at one end, said sides being provided, near the base of the U and near the ends of the sides, with projecting struts, and longitudinal tension 95 members connecting the front and rear struts.

7. An engine frame comprising a frame member of general U-form, the sides of the U being integrally connected at one end, 100 said sides being provided, near the base of the U and near the ends of the sides with projecting struts, longitudinal tension members connecting the front and rear struts, and a transverse rod connecting the front 105 struts.

8. An engine frame comprising a frame member of general U-form, the sides of the U being integrally connected at one end, said sides being provided, near the base of the U 110 and near the ends of the sides with projecting struts, longitudinal tension members connecting the front and rear struts, a transverse rod connecting the front struts, and another rod connecting the sides of the U 115 near the bases of the struts.

9. A horizontal engine frame comprising sides connected to each other and provided at front and rear with upwardly projecting struts, tension rods connecting such struts 120 and a hoist mounted on said rods and movable therealong, the said rods constituting ways for the hoist.

10. A horizontal engine frame comprising a horizontal frame member of general U-form provided at one end with an engine cylinder constituting an integral portion of the frame, the sides provided with upwardly extending struts, longitudinal tension members connecting said struts, the 125 130

frame being open from the front of the cylinder to said struts, and a hoist mounted upon said tension members and movable therealong from the front struts to in proximity to the front of the engine cylinder, said tension members forming ways for the hoist.

11. The combination, with an engine frame and cylinder and cylinder head, of a valve gear bracket secured to said engine frame and located in proximity to said cylinder head, but entirely disconnected from the cylinder head.

12. An engine frame comprising in an integral structure a frame and engine cylin-

der, said cylinder having a rear face adapted for the reception of a separate cylinder head, said frame having, projecting from its rear, a boss, adapted for the reception of a part to be attached to said frame, the end 20 face of such boss being flush with the end face of the cylinder.

In testimony whereof I have signed this specification in the presence of two subscribing witnesses.

LEON WYGODSKY.
